Louis Dagger & Co.

UNITED STATES PATENT OFFICE.

CHARLES RICHARD SWAN, OF BOIS BRULE, MISSOURI, ASSIGNOR OF ONE-THIRD TO BENJAMIN FRANKLIN WILKINSON AND WALTER SCOTT WILKINSON, OF SAME PLACE.

CRATE.

SPECIFICATION forming part of Letters Patent No. 372,992, dated November 8, 1887.

Application filed August 18, 1887. Serial No. 247,249. (No model.)

To all whom it may concern:

Be it known that I, CHARLES RICHARD SWAN, a citizen of the United States, and a resident of Bois Brule, in the county of Perry and State of Missouri, have invented certain new and useful Improvements in Crates and Boxes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a knock-down or folding crate constructed according to my invention. Fig. 2 is a perspective view showing the several parts of the crate separated. Fig. 3 is a perspective view showing the crate folded for transportation or for packing it away when not in use, and Fig. 4 is a view of a dry-goods box constructed according to my invention.

The same letters of reference indicate corresponding parts in all the figures.

My invention consists in certain new and improved crates or boxes with their fastening devices, which are adapted to be folded for transportation or storage, and which will be hereinafter fully described and claimed.

Referring to the several parts by letter, A indicates the flat solid bottom of a crate for fruit, &c., constructed according to my invention. On the top or upper side of the ends of this bottom board, A, are secured the transverse strips B B, and upon the upper side of the bottom board, parallel with these end strips and at a short distance from the same, are secured the shorter inner transverse strips, C C, leaving the parallel spaces D D between the end strips, B B, and the respective inner strips, C C, as shown.

Across the bottom or lower side of the bottom board, A, are firmly secured the transverse flat metal bands or strips E E, which extend nearly across the bottom beneath the inner strips, C C, and the ends of which extend out beyond the sides of the bottom plate. These ends are formed each with the perforation F, for the purpose hereinafter described.

G G indicate the nearly-square end pieces of the folding crate, which are formed with side, top, bottom, and cross pieces in the usual manner. These end pieces fit at their lower ends in the transverse spaces D D at the ends of the bottom board, between the end strips, B B, and the inner end strips, C C, the length of these end pieces being somewhat less than the width of the bottom board, so as to leave a small space at each of their ends.

H H indicate the side pieces of my improved folding crate, each of which is formed of the longitudinal parallel pieces or strips or bars H' and the two end posts or uprights, H² H². The end posts or uprights are secured to the parallel horizontal slats or bars H' at a little distance from the ends of the same, as shown. Thus when the side pieces are placed in position on the sides of the bottom board the outer sides of the posts or uprights H² H² will be in contact with the inner sides of the ends of the end pieces, G G, the side and end pieces being thus braced together. The outer ends of the longitudinal slats or bars of the side pieces bear against the ends of the end pieces, while the ends of the end pieces, on their inner sides, bear against the end posts or uprights of the side pieces, as shown.

Through the perforated ends of the metal straps E E on the bottom of the bottom board, near the ends of the same, pass the threaded stems of eyebolts I I, the said stems passing down and having nuts J screwed on their lower ends below the perforated ends of the metal straps, as shown. In the eyes at the upper ends of these eyebolts are hinged the bent lower ends of the metal bails K. Each of the said bails is formed of a single bar of iron bent at each end so as to form the straight central portion, K', which extends over the top of the crate, and the ends or side pieces, K² K², which extend down on each side of the crate at right angles to the middle upper portion. Each bail has its lower ends bent to form eyes K³ K³, which hook into the eyes on the tops of the eyebolts I I, as shown. The eyebolts I I stand with their broad heads or eyes at right angles to the side of the crate, so that when the side pieces of the crate are placed in position in putting

the crate together the inner sides of the eyes of the eyebolts will be in contact with the outer sides of the side pieces and will serve to hold them in position while the crate is being filled, before the top thereof has been placed on in position to close the crate. The side pieces and end pieces having been placed in position on the bottom board, A, as described and shown, the top L is then placed in position. This top L is formed with the transverse end strips, M M, on its lower side, as shown, the top being of such length that when placed in position on the crate the end strips, M M, will fit over outside of the upper ends 15 of the end pieces, G G. As the end strips on the lower side of the top L thus fit over outside of the upper ends of the end pieces of the crate, and the ends of these end pieces bear against the end uprights or posts of the 20 side pieces, H H, it will be seen that when the top is placed down in position on the top of the crate it will bind the end pieces in against the end uprights of the side pieces, H H, and will thus assist in binding the several parts of 25 the folding crate together in their operative positions, assisting in rendering the crate strong and stable and preventing it from being knocked out of shape while in transit or while being handled.

30 The nuts J on the lower ends of the eyebolts are screwed down or loosened, so that when the top L has been placed in position the end bails, K K, which have swung down and out so as to rest upon the ground or floor while 35 the crate was being placed together, can now be swung up, so that their central longitudinal parts, K', will pass up over the ends of the top of the crate until the sides of the bails are in a straight line with the stems of the 40 eyebolts, as shown in Fig. 1. In this position the straight horizontal middle portions of the two end bails extend squarely over the end portions of the top of the crate near the ends of the same. When the bails are up in this 45 position, the nuts on the lower ends of the threaded eyebolts I I are screwed up, so as to draw the stems of the eyebolts down through the perforated ends of the metal cross-bands E E, and thus draw the bails K K down, so 50 that the central horizontal portions bear down firmly upon the top of the crate near the ends of the same. It will be seen that when the nuts on the lower ends of the eyebolts have 55 been screwed up tight, so as to draw the metal bails down tightly on the top of the crate, a metal band will be drawn tightly around each end of the crate, formed by the metal bottom straps or bands, E E, the eyebolts with their nuts, and the bails with their central 60 and side parts, as shown and described, and that these two metal bands will firmly and strongly bind the crate and hold it securely in its closed position, making the crate as solid and strong as a box built with permanently- 65 fixed solid sides, ends, and top could possibly be.

Where a box with solid sides, ends, and top

is desired, instead of a crate for packing and shipping purposes, it can be constructed in accordance with my invention, as shown in 70 Fig. 5 of the drawings. In this form I have shown a solid bottom having the outer end strips, but not the inner strips, (which may be employed or not in this form of my invention, as desired,) the eyebolts, with their 75 nuts and the metal bails, and the metal straps or bands with the perforated ends extending across the bottom of the box. The end pieces, the side pieces, and also the top of this form are constructed solid, and the ends of the side 80 pieces are preferably connected by a long hook-bar, O, which is hinged at one end to one of the side pieces. The free hooked end of the bar engages with a staple, P, on the end of the other side piece, as shown, thus 85 holding the end piece in position as well as holding the side pieces firmly against the end pieces, as shown. The top is secured in position on the box by the bails, in the same manner as in the crate, before described. 90 This box does not differ in any material form from the crate, both embodying the same features, and it may be employed in place of the crate when so desired.

The crate may be packed up for shipment or 95 storage, so as to occupy but one-half the space it occupies when open, by laying the end pieces down flat upon the bottom, then placing the side pieces over them flat, and finally placing the top down flat on the whole. The bails are 100 then swung or turned over the whole, so as to meet in the middle, where they are tied together, when the whole crate will be thus folded and secured in a small compass, as shown in Fig. 4 of the drawings. Two crates may be folded 105 up and packed together so as to occupy only the space of one when unfolded by first packing the ends and sides of the first crate down, as described, leaving the bails out, however, and then placing the ends, sides, and top of 110 the second crate on the first, when the bails of the first are then brought up and screwed down tight. The bottom of the second crate is 115 then placed over this package and the bails of the second bottom are passed under the ends of the first bottom and screwed tight, as will be readily understood, when the two crates will take up only the space occupied by one when open.

In the top of the crate I provide an opening, 120 which affords access to the interior of the crate when the top thereof has been secured in position by the bails. This opening is closed by a removable lid, S, the outer end of which rests upon one end cross-piece of the crate-top. It 125 is formed with a central notch or recess, S'. This engages with a headed stop or nail, T, on the cross-piece when the lid is slid into its closed position, the said headed stop serving to hold that end of the lid down shut. The 130 other end of the lid, which rests upon the central cross-piece of the crate-top, is formed with a central recess, S", in which fits the inner end of the middle half-slat a of the crate-top, and

when the lid is slid into position it is retained in place by a turn-button, U, centrally pivoted on the inner end of the half-slat, which may be turned longitudinally of the slat to permit of the removal or raising of the lid S, and which is turned transversely over that end of the lid to hold it in place.

From the foregoing description, taken in connection with the accompanying drawings, the construction, operation, and advantages of my invention will be readily understood.

It will be seen that my improved crates and boxes are simple and exceedingly strong in construction, and by their use fruit can be packed in crates or boxes without danger of bruising it by nailing, and can be crated and boxed in better shape.

Having thus described my invention, what I claim, and desire to secure by Letters Patent of the United States, is—

1. The combination, with the bottom having the end strips, of the side pieces having the end posts on their inner sides, the end pieces, the top having the end strips on its lower side, the metal strips secured beneath the bottom and having the perforated projecting ends, the eyebolts having the threaded

stems and the nuts, and the bails, substantially as set forth.

2. The combination, with the bottom having the outer and inner parallel end strips, of the side pieces having the end posts on their inner sides, the end pieces, the top having the end strips on their lower side, the metal strips secured beneath the bottom and having the perforated projecting ends, the eyebolts having the threaded stems and the nuts, and the bails, substantially as set forth.

3. The combination, with the crate composed of the bottom, the side pieces, and the end pieces, of the top formed with the middle half-slat having the turn-button at its inner end and having the nail or headed stop on the center of its end cross-piece, and the removable lid formed with the notch in its outer end and the central recess in its inner end, substantially as and for the purpose set forth.

In testimony that I claim the foregoing as my own I have hereunto affixed my signature in presence of two witnesses.

CHARLES RICHARD SWAN.
